UNITED STATES PATENT OFFICE.

GEORGE WILLIAM BELDAM, OF EALING, ENGLAND.

ENGINE OR MACHINE PACKING.

No. 835,744.

Specification of Letters Patent.

Patented Nov. 13, 1906.

Application filed December 7, 1905. Serial No. 290,832.

To all whom it may concern:

Be it known that I, GEORGE WILLIAM BELDAM, a subject of the King of England, residing at Ealing, in the county of Middlesex, England, have invented a new and useful Improved Engine or Machine Packing, of which the following is a specification.

This invention has reference to packings used in engines or machines for making a tight joint between a moving part, such as a rod or plunger, and a stationary part, such as a cylinder cover or end, or other part of the engine, pump, or machine in connection with which the rod or plunger works and from which it is desired to prevent the escape of fluid or into which the entrance of fluid is to be prevented; and the primary object and effect of the present invention is to provide in or in connection with packings comprising asbestos, canvas, or other soft or pliable fabric a solid white metal or analogous metal which is capable of being readily bent, so as to be easily formed or adjusted to suit different sizes of piston and other rods or parts to which it is to be applied.

Asbestos, canvas, or other suitable fabric (or such material in combination with strips of plaited or plain thin metal or the like) which is to form the base or body of the packing and in connection with which the solid white or like metal bar or strip or a plurality of bars or strips is or are to be combined is folded into continuous folds, between which folds are inserted a bar or bars or strip or strips of white or other suitable metal or mixture, and according to this invention the section of the metal strips or bars is such that it will embed itself between the folds in such a manner that it will "key" itself in the material, and, further, the metal of the section or sections referred to is slotted or cut in a diagonal or oblique direction to allow the metal to bend or conform to the piston-rod or surface against which it comes in contact more easily. The diagonal slots or cuts or grooves extend diagonally or obliquely to the direction of the axis of the rod to be packed—that is, at an oblique angle to the direction of length of the metal—and they are of any suitable shape and possess a distinct advantage, in that when they meet and come in contact with the piston or other rod they form an angle "across" the surface of the rod, and "scoring" of the rod, which is liable or likely when the slots are vertical, is reduced to a mini-

mum. The diagonal slots or cuts in the metal bars extend from the face which will come next the rod and which will be flush with the working face of the packing generally to a part near the base or back side of the bar or strip.

The invention is illustrated in the accompanying drawings, and its further description will be made by their aid.

In the drawings, Figures 1 and 2 are perspective views showing my invention in cross-section, in which the soft portion or body of the packing is in different forms. Figs. 3 and 4 are two perspective views of the metal bar or strip according to this invention, showing it in the position lying on its side and when standing on its lower edge or face, respectively.

Referring now to the drawings, *a* generally designates the metal bar, and *e* is the outer main body of the packing.

In Fig. 1 the main body of the packing is designated *e*, and consists of parallel laminae of textile material, as asbestos, canvas, or any other suitable fabric or a combination of such fabric and metal sheets, such as plaited metallic sheets or plain thin sheets or wire gauze.

In Fig. 2 the body *e* may be taken to be made of the same character of materials, but with the plaits or folds of laminae of the materials lying in a plane at right angles to the plane of the bar *a*, the other being parallel with the bar *a*. As shown, this bar *a* is enclosed by and lies in the space within the laminae of the body material *e*, its working edge being flush with that of the body *e*, and the part of the bar *a* which lies within the working face of the packing is of greater depth or thickness at one part than another, so that the part of the material of the body *e* which lies on or next the thinner part keys and positively holds the bar in position, and it cannot shift or come away from the body.

The backing of the body *e* of the packing may be made of canvas, asbestos, or textile or any suitable material, or such material in combination with thin metallic sheet metal, or of any suitable materials.

In the section or form of bar shown in the drawings there is a bulb or enlarged part *b* at the back edge, and it extends in size from the narrowest part toward the working edge or face somewhat in the form or section of a keyhole. Various modifications, however, of

this section may be employed by which the "keying" effect or method is accomplished.

The oblique slots or cuts *c* extend from the outer edge or working face of the bar to the narrow part just within the head *b*, and they allow the side of the metal which comes in contact with the piston-rod to close as the back portion or side away from the rod bends, and they have a slight tendency to slide on one another. The bending of the rod as stated causes the slots to close or meet, and they are advantageous, especially with packings arranged in spiral form—that is, not in cut rings—owing to the fact that the longer the rod of metal the upward sliding tendency of the slots or cuts is increased. In the shorter lengths, such as that suitable for ring form, this increase is not so marked.

The folds of canvas, asbestos, or the like, or canvas, asbestos, in conjunction with plaited or plain strips of metal, are all suitably adhered together by solution or other adhesive and pressed and shaped to the required shape and form.

The packing above described bends easily to the piston or other rod and forms an efficient packing, while the metal bar or bars or strip or strips is or are effectually held in place.

What is claimed is—

1. Improved engine or machine packing comprising a body made of pliable material, and a metal bar of suitable flexible metal, narrower at a point between the inner edge and the outer working face, whereby said metal is "keyed" in position when embedded within the fabric of the body, and held therein, and having gaps extending between its working face and points toward the back portion, and disposed in an oblique angle to the direction of length of the metal; substantially as set forth.

2. An engine or machine packing comprising a body made of laminae of pliable material suitably held together, and a metal bar of flexible metal embedded in it, which at a part within the working face is of different thickness at different points, and has a series of gaps extending between its working face and a point near the back of same; substantially as set forth.

In testimony whereof I have signed my name to this specification in the presence of two subscribing witnesses.

GEORGE WILLIAM BELDAM.
